George Haviland Inventor
By his Attorney
Chas. C. Gile

UNITED STATES PATENT OFFICE.

GEORGE HAVILAND, OF LIMOGES, FRANCE.

DESIGN FOR A CUP OR SIMILAR ARTICLE.

59,219.

Specification for Design.

Patented Oct. 4, 1921.

Application filed May 23, 1921. Serial No. 471,980. Term of patent 14 years.

To all whom it may concern:

Be it known that I, GEORGE HAVILAND, a citizen of the United States, residing at Limoges, France, have invented a new, original, and ornamental Design for a Cup or Similar Article, of which the following is a specification, reference being had to the accompanying drawing, forming a part thereof, and in which—

Figure 1 is a top or plan view, and Fig. 2 is a side elevation of a cup embodying my design.

I claim:
The ornamental design for a cup or similar article, as shown.

GEORGE HAVILAND.
